(57) **CLAIM**

The ornamental design for a projectile launcher, as shown and described.

DESCRIPTION

FIG. 1 is a perspective view of a projectile launcher in accordance with our invention;

FIG. 2 is a rear view thereof;

FIG. 3 is a front view thereof;

FIG. 4 is a top view thereof;

FIG. 5 is a bottom view thereof; and,

FIG. 6 is a side view thereof, an opposing side view being a mirror image thereof.

The dashed lines in the drawings show environmental structure and form no part of the claimed design. The dashed lines immediately adjacent to a shaded area define the bounds of the claimed design and form no part thereof.
